DESIGN FOR A LUBRICANT DISPLAY HOLDER

Mustafa I. Hakky, Glendale, R. I.

Application February 16, 1937, Serial No. 67,689

Term of patent 7 years

To all whom it may concern:

Be it known that I, Mustafa I. Hakky, a citizen of the Republic of Turkey, residing at Glendale, in the county of Providence and State of Rhode Island, have invented a new, original, and ornamental Design for a Lubricant Display Holder, of which the following is a specification, reference being had to the accompanying drawing, forming part thereof.

Fig. 1 is a side elevational view of the lubricant display holder showing my new design, and Fig. 2 is a horizontal section, taken along the line 2—2 of Fig. 1, showing a top plan view of one of the holder sections.

What I claim is:—

The ornamental design for a lubricant display holder, substantially as shown.

MUSTAFA I. HAKKY.
